UNITED STATES PATENT OFFICE

CLIFFORD E. BAUM, OF SYCAMORE, OHIO

ADVERTISING SIGN FOR FENCES

Application filed March 4, 1930. Serial No. 433,075.

This invention pertains to improvements in signs and especially advertising signs which are disposed along much traveled country roads, highways and the like.

5 The prime object of the invention is to provide a simple, strong, durable and comparatively inexpensive advertising sign adapted to be fixedly secured to wire fences of the type such as is set forth in the patent granted 10 to me under date of September 3, 1929, No. 1,726,878, said sign being so secured and anchored that it cannot be readily misplaced by the wind or live stock.

A further object of the invention is to 15 provide a sign that can be conveniently disposed on private property adjacent to the thoroughfare with the sign at right angles to the roadway within easy vision of drivers of vehicles and travelers, with no part of the 20 sign overhanging the public property, said sign possessing characteristics that in no way detract from the scenic beauty of the thoroughfare.

Another object of the invention is to so 25 construct the sign that it may be readily secured to a portion of the wire fence without erecting any special means other than the fence proper for supporting said sign.

The foregoing and such other objects as 30 may appear from the ensuing description are accomplished by the construction, location and combination of the several parts herein- 35 after more fully described and particularly pointed out in the claims appended hereto, it being understood that slight changes in the precise shape, proportions and minor de- 40 tails of construction may be resorted to without departing from the spirit or sacrificing any of the advantages of the invention.

45 In the accompanying drawings forming a part of this specification it will be seen that:

Figure 1 is a perspective view of a portion of a wire fence with a sign connected therewith embodying my invention.

45 Figure 2 is a side elevation of a slightly modified fence guard arm and post for supporting the sign.

Figure 3 is a plan of the means shown in Fig. 2.

50 Figure 4 is a side elevation of another

slightly modified form showing the sign secured at an angle with relation to the post.

Figure 5 is a plan of the means shown in Fig. 4.

Figure 6 is a side elevation of another 55 slightly modified form showing the sign secured to a different form of post and guard arm, and

Figure 7 is a plan of the modified form, such as is shown in Fig. 6.

In the embodiment of my invention as illustrated, it will be seen by reference to Fig. 1 that the numeral 2 designates a metallic wire fence post of the L-shaped type, and to the upper end portion thereof is rigidly and 60 fixedly secured a guard arm 3, adapted to extend any suitable or desirable distance inwardly, said arm being provided at its inner end portion 4, with a slot 5, for the reception of a guard wire 6, which will successfully 65 prevent stock from approaching too close to the fence, hence they will be unable to damage the fencing or to interfere with the sign hereinafter referred to.

The sign panel or sheet 7 is preferably 70 made from vitrified iron and formed through its upper end portion is a series of openings or slots 8 with brass or brass lined eyelets 9 and adjacent the post 2 at the lower end portion of the sign plate 7 is another opening 80

8' provided with brass or brass lined eyelet, thus making the sign plate, in its entirety, practically rust-proof. The sign is secured at its upper horizontally disposed end portion to the inverted L-shaped guard arm 3, 85 by a series of what are known in the trade as "hog rings" or heavy strong wires 9' which are passed through suitable openings 10 formed through the guard arm and 90 through the openings 8, said openings 8 and 10 being in vertical alinement with relation to each other, and passed through the opening 8' and around the post, is a heavy strong wire member or stay 11 by which the lower 95 end portion of the sign is fixedly secured to the post, thus the sign properly is so secured to the guard and post of the fence that it cannot be readily misplaced, and both its front and rear face are artistically painted 100 with any suitable advertising sign including

letters, symbols, or both, (not shown) that may be desirable for advertising purposes.

The modified form such as is shown in Figs. 2 and 3, shows a wooden post 12 to which is rigidly secured a guard arm 13, to which post and arm a sign plate 14 is fixedly secured in the manner substantially as hereinbefore described.

Figs. 4 and 5 of the drawings illustrate the sign plate 15, rigidly secured to a post 16 and guard arm 17 at an angle with relation to the post, while Figs. 6 and 7 disclose a further modified form of fence post 18 and guard arm 19 with the sign plate 20 secured thereto in the manner hereinbefore referred to.

It will be readily perceived that this particular construction and type of sign may readily and easily be fixedly and permanently secured to the ordinary wire fence now employed along much traveled thoroughfares and highways without the necessity of erecting additional securing posts, or other means for securing the sign plate so that it cannot be readily displaced, and further that the sign is composed of such material as to considerably increase its longevity and prevent early deterioration thereof, also that it is preferably disposed at right angles with relation to the fence, and that it is always located on private property.

It will be readily understood that signs of various types may be secured to the wire fence at a point or points intermediate the fence posts on private property either parallel or at an angle of 90° to the highway, by suitably securing the sign to the barbed fence wire and the guard wire secured to the guards on the fence posts.

Having thus described my invention what I claim and desire to secure by Letters Patent is:

1. An advertising sign for wire fences disposed along public highways, comprising a metallic post for the reception of a series of wires, a guard arm fixedly secured to the upper end portion of the post, said guard arm having an opening formed therethrough at its inner end portion for the reception of detachable guard wire and a series of slotted openings therethrough formed in horizontal alinement intermediate its ends, a sign plate with a series of openings formed in horizontal alinement through its upper end portion disposed in vertical alinement with the slotted openings in the guard arm, a series of metallic links passing through all of said openings in the sign plate and guard arm for securing said plate to the guard arm, an opening formed through the lower end portion of the plate, and a wire passing through the last-named opening and attached to the post for securing the lower end of the plate to said post.

2. An advertising sign for wire fences disposed along public highways, comprising a post for the reception of a series of fence wires, an inwardly extended guard arm fixedly secured to the post, said guard arm having an opening therethrough at its inner end portion for the detachable reception of a guard wire and a series of horizontally disposed slotted openings formed therethrough intermediate its ends, a sign plate formed of vitrified iron having a series of openings formed therethrough in horizontal alinement at its upper end portion disposed in vertical alinement with said slotted openings, supporting rings passing through the openings in the guard arm and sign plate for securing said plate to the guard arm, an opening formed through the lower end portion of the sign plate, and a wire member passing through the last-named opening and secured to the post for fixedly securing the lower end of the sign plate to said post.
